UNITED STATES PATENT OFFICE.

ALBERT SÖDERBLOM, OF LAKEFIELD, MINNESOTA.

DESIGN FOR A PICTURE-FRAME.

46,454.

Specification for Design.

Patented Sept. 22, 1914.

Application filed July 29, 1914. Serial No. 853,963. Term of patent 7 years.

To all whom it may concern:

Be it known that I, ALBERT SÖDERBLOM, a citizen of Sweden, residing at Lakefield, in the county of Jackson and State of Minnesota, have invented a new, original, and ornamental Design for Picture-Frames, of which the following is a specification, reference being had to the accompanying drawing, forming part thereof.

The figure is a front view of a picture frame, showing my new design.

I claim:

The ornamental design for a picture frame, as shown.

ALBERT SÖDERBLOM.

Witnesses:

ABE SWANSON,
O. SHWEHN.
